UNITED STATES PATENT OFFICE

THOMAS J. HOWLAND, OF LONG BRANCH, NEW JERSEY

BATHING CAP

Application filed April 22, 1929. Serial No. 356,842.

This invention relates to bathing caps and provides for a cap which forms a watertight seal along its edge and prevents moisture from penetrating within the interior of the cap.

- 5 A great variety of methods have been proposed for rendering bathing caps watertight but none of them have proved very satisfactory as is witnessed by the fact that bathing caps at present on the market usually consist 10 of a simple rubber cap. A simple rubber cap is far from satisfactory and moisture generally seeps in at the edge of the cap rendering the cap totally ineffective for the purpose for which it is used.
- 15 The present invention provides a bathing cap which is adapted to form a watertight seal along the edge of the cap. This is accomplished without excessive tightening at the edge portion which would bind the head 20 and cause discomfort to the wearer.

A plurality of cups or air pockets are provided around the inside edge of the cap. These are formed by ribs projecting from the cap toward the inside and adapted to contact 25 with the head of the wearer of the cap. Means are provided for pressing the ribs into close engagement with the skin along the edge of the cap. The hollows or cups between the ribs tend to increase the effectiveness of the 30 seal due to the suction effect of these cups which act as vacuum cups.

The ribs which are in close engagement with the skin along the edge of the cap present a series of sealing surfaces separated 35 by air pockets. The ingress of water or moisture is prevented therefore by a series of effective barriers.

The elasticity of the material composing the cap may be taken advantage of to press 40 the band of ribs into close engagement with the skin and, if desired, a chin band may be used.

There is further advantage in placing a fluid chamber along the edge of the cap which 45 will ensure that the band of ribs will be pressed into all the irregularities of the head.

If protruding elements are used which are adapted to fit in the most prominent irregularities of the head less pressure will be required to press the band of crossed ribs into

close engagement with the skin at such points.

For an example of a bathing cap embodying my invention reference is made to the accompanying drawing in which

Fig. 1 is a side elevation of the bathing cap;

Fig. 2 is a cross section taken through the rim of the cap;

Fig. 3 is a cross section taken through line 3—3 of Fig. 1;

Fig. 4 is a cross section taken through line 4—4 of Fig. 2, and

Fig. 5 is a plane view of a section of the inside band of crossed ribs arranged along the edge of the cap.

The bathing cap 10 comprises a main portion 11 of elastic material. This main portion is shaped to fit the general contour of the head.

Along the inside edge of this main portion 11 is attached a band comprising a series of crossed ribs 12 forming hollows or cups 13 therebetween. In Fig. 5 a section of this band of crossed ribs is illustrated.

The hollows or cups 13 are shown as diamond shaped and while this particular form has been found effective other forms can be used with good results, e. g., the hollows or cups 13 may be round or square, or oval shaped, etc. Furthermore, while in Fig. 5 the 80 band of crossed ribs 12 comprises several rows of hollows or cups 13, I do not wish to restrict myself to the form shown, as even a single row of cups due to the suction effect of the cups will tend to maintain the edge of the 85 cap in close engagement with the skin and form a watertight seal.

The elasticity of the material composing the main portion 11 of the cap will tend to press the crossed ribs 12 into close engagement with the skin and the cups 13 by their suction effect will tend to maintain this engagement.

The ribs 12 should have sufficient rigidity so that when stretched they will not upset and destroy the vacuum effect of the cups. The 95 rigidity of the ribs 12 depends on the material of which they are formed, their width and the depth of the cups. The ribs are more effective as sealing surfaces if they are narrow as shown in Fig. 5, but the invention is not 100

limited to this form and the width of the ribs 12 need not be uniform.

As shown in the drawings the band of crossed ribs 12 consists of a separate strip 14 attached to the edge of the main portion 11 in some convenient manner, but it is evident that the crossed ribs 12 might be formed directly in the main portion 11. The band 12 is shown as being disposed along the entire inside edge 10 of the main portion 11 of the cap and this is the most effective arrangement. But the band may be interrupted, for instance, at the point covering the forehead, without materially affecting the result. The shape of the head 15 at this point is such that the edge of the cap is in such intimate contact with the skin that there is little danger of any seepage of water at this point and the gripping effect of the ribs at other points will prevent the cap from being jerked off.

20 The suction effect of the cups 13 tends to maintain the engagement of the edge of the cap with the skin and will prevent the cap from being pulled off the head thus eliminating the necessity of a chin band. A chin band 15, however, may be attached to the outer edge of the main portion 11 to increase 25 the pressure along the edge of the cap.

20 The pressure exerted on the band of crossed ribs 12 due to the elasticity of the material composing the main portion 11 may be supplemented by providing an air or fluid chamber 18 along the outer edge of the cap. This chamber 18 is formed by attaching a strip 17 35 of elastic material to the outer edge of the main portion 11. The strip 17 should preferably consist of a material having less elasticity than the material comprising the main portion 11. A fluid is inserted within the 40 chamber 18. The chamber 18 may then be permanently sealed or a valve 19 may be placed in the strip 17 so that the pressure exerted by the fluid may be varied to suit the wearer. The pressure exerted by the 45 fluid in the chamber 18 forces the crossed ribs 12 into all the irregularities of the head and presses the crossed ribs into close engagement with the skin at all points. A bead 21 may be placed along the outside edge to reinforce 50 the same.

As shown in the drawings the chamber 18 extends completely around the cap but the chamber might be arranged to extend only partly around the cap at such points where 55 it would be most effective, such as at the back of the head.

As previously explained, if protruding elements are arranged on the cap so as to fill in the most prominent irregularities of the head 60 less pressure will be required to press the band of crossed ribs 12 into close engagement with the skin at such points.

To this end, tapered elements 20 may be placed between the main portion 11 and band 65 of crossed ribs 12 at such a location that they

will fit into prominent hollows in the head. As shown in Fig. 3 the tapered elements 20 are shaped and located to fit into the hollows below the ears and at the nape of the neck of the wearer.

If a chin band 15 is used, it should preferably be attached to the outside of the cap and tapered elements 20 may be positioned at the outside edge of the cap as shown in Fig. 70 1 or between the main portion 11 and the band of cross ribs 12 as previously described. In either case the effect of the tapered elements 75 it to offset the chin band slightly from the cap and thereby to cause a more secure engagement of the edge of the cap below the ears when the chin band is fastened under the chin of the wearer.

While the invention has been particularly described in connection with a bathing cap which is to be applied to the head of the 80 wearer, it is clear that the invention may be incorporated in bathing caps for enclosing other body members.

I claim:

1. An article of bathing apparel comprising 90 a pocket having a main portion of elastic, waterproof material, said pocket having a body-gripping edge portion, at least a portion of such edge portion being provided with cups or air pockets which, due to the elasticity 95 of the material, contact the body of the wearer and prevent the passage of water beneath the edge of the pocket at those places, thereby rendering the pocket watertight when in use.

2. An article of bathing apparel comprising 100 a pocket having a main portion of elastic, waterproof material, said pocket having a body-gripping edge portion, at least a portion of such edge portion being provided with cups or air pockets formed by ribs projecting 105 from the article toward the inside which, due to the elasticity of the material, contact with the body of the wearer and prevent the passage of water beneath the edge of the pocket at those places, thereby rendering the 110 pocket watertight when in use.

3. A bathing cap comprising a main portion of elastic, waterproof material having a body-gripping edge portion, at least a portion of said edge portion being provided with 115 cups or air pockets formed by ribs projecting from the cap toward the inside which, due to the elasticity of the material, contact with the head of the wearer and prevent the passage of water beneath the edge of the cap at those 120 places, thereby rendering the cap watertight when in use.

4. A bathing cap comprising a main portion of elastic, waterproof material, having a body-gripping edge portion, at least a portion of such edge portion being provided with cups or air pockets formed by ribs projecting from the cap toward the inside which, due to the elasticity of the material, contact with the head of the wearer and prevent the passage 125 130

of water beneath the edge of the cap at those places, thereby rendering the cap watertight when in use, said air pockets being arranged so that water in tending to pass from the edge to the inner portion of the cap must traverse 5 more than one air pocket.

5. A bathing cap comprising a main portion of elastic, waterproof material having a body-gripping edge portion, at least a portion of such edge portion being provided 10 with cups or air pockets formed by ribs projecting from the cap toward the inside which, due to the elasticity of the material, contact with the head of the wearer and prevent the 15 passage of water beneath the edge of the cap at those places, thereby rendering the cap watertight when in use, said main portion having also at certain portions of its edge 20 projections adapted to fit into hollows in the contour of the head.

6. A bathing cap comprising a main portion of elastic, waterproof material having a body-gripping edge portion, at least a portion of such edge portion being provided 25 with cups or air pockets formed by ribs projecting from the cap toward the inside which, due to the elasticity of the material, contact with the head of the wearer and prevent the 30 passage of water beneath the edge of the cap at those places, thereby rendering the cap watertight when in use, said main portion having attached to it a chin strap adapted 35 to hold said ribs more firmly in contact with the head.

7. A bathing cap comprising a main portion of elastic, waterproof material having a body-gripping edge portion, at least a portion of said edge portion being provided with 40 cups or air pockets formed by ribs projecting from the cap toward the inside which, due to the elasticity of the material, contact with the head of the wearer and prevent the 45 passage of water beneath the edge of the cap at those places, thereby rendering the cap watertight when in use, and means for pressing said ribs into engagement with the head.

8. A bathing cap comprising a main portion of elastic, waterproof material having a body-gripping edge portion, at least a portion 50 of said edge portion being provided with cups or air pockets formed by ribs projecting from the cap toward the inside which, due to the elasticity of the material, contact with the head of the wearer and prevent the 55 passage of water beneath the edge of the cap at those places, thereby rendering the cap watertight when in use, said main portion having also at certain portions of its edge 60 projections adapted to fit into hollows in the contour of the head, and a fluid chamber arranged along the outside edge of said main portion adapted to press said ribs into close engagement with the head.

9. A bathing cap comprising a main portion 65 of elastic, waterproof material having a

body-gripping edge portion, at least a portion of such edge portion being provided with a series of crossed ribs forming cups therebetween which, due to the elasticity of the material, contact with the head of the wearer and prevent the passage of water beneath the edge of the cap at those places, thereby rendering the cap watertight when in use. 70

10. A bathing cap comprising a main portion of elastic, waterproof material having a body-gripping edge portion, at least a portion of such edge portion being provided with a series of crossed ribs forming cups therebetween which, due to the elasticity of the material, contact with the head of the wearer and prevent the passage of water beneath the edge of the cap at those places, thereby rendering the cap watertight when in use, and tapered projections adapted to fill in 75 irregularities of the head.

11. A bathing cap comprising a main portion of elastic, waterproof material having a body-gripping edge portion, at least a portion of such edge portion being provided with a series of crossed ribs forming cups therebetween which, due to the elasticity of the material, contact with the head of the wearer and prevent the passage of water beneath the edge of the cap at those places, thereby rendering the cap watertight when in use, 80 and tapered projections adapted to fill in irregularities of the head and means for pressing said crossed ribs and said tapered projections into close engagement with the skin. 85

12. A bathing cap as described in claim 10 which comprises a fluid chamber arranged along the outside edge of the cap adapted to press the edges of said cap into close engagement with the skin.

In testimony whereof I affix my signature. 105
